(57) **CLAIM**

The ornamental design for a bottle as shown and described.

DESCRIPTION

FIG. 1 is a front, right, and top perspective view showing my new design.

FIG. 2 is a front view showing my new design.

FIG. 3 is a rear view showing my new design.

FIG. 4 is a left side elevational view showing my new design.

FIG. 5 is a right side elevational view showing my new design.

FIG. 6 is a top view showing my new design; and,

FIG. 7 is a bottom view showing my new design.

The shading lines shown in the drawings represent the approximate three-dimensional contour of the design, and are not intended to indicate surface decoration.

The broken line showings of the pockets and cap are provided for purposes of environment and form no part of the claimed design.

1 Claim, 7 Drawing Sheets
